By Bonesticker.

UNITED STATES PATENT OFFICE.

GEORGE TAUSE CAMPBELL, OF SAN FRANCISCO, CALIFORNIA, ASSIGNOR OF
ONE-HALF TO JAMES CAMPBELL, OF SAME PLACE.

LADDER.

SPECIFICATION forming part of Letters Patent No. 451,893, dated May 5, 1891.

Application filed October 6, 1890. Serial No. 367,148. (No model.)

To all whom it may concern:

Be it known that I, GEORGE TAUSE CAMPBELL, a naturalized citizen of the United States, residing in the city and county of San Francisco and State of California, have invented certain new and useful Improvements in Ladders; and I do hereby declare the following to be a full, clear, and exact description of said invention, such as will enable others skilled in the art to which it most nearly appertains to make, use, and practice the same.

My invention has relation to certain new and useful improvements in ladders, which consists of the arrangement of parts and details of construction, as will be hereinafter more fully set forth in the drawings and described and pointed out in the specification.

The invention relates more especially to improvements in fruit-ladders; and it consists in providing supplemental supports whereby the ladder will be prevented from tilting laterally and falling over, thereby preventing liability of the user thereof being thrown therefrom.

My invention further consists in providing the ladder with an adjustable holding device whereon the basket may be secured for holding of the picked fruit.

Referring to the drawings, forming a part of this specification, wherein similar letters of reference are used to denote corresponding parts throughout the entire specification and several views, Figure 1 is a perspective view in elevation; Fig. 2, a broken longitudinal sectional view.

The letter A is used to indicate an ordinary ladder provided with the usual supports B. To the under face of the platform a, I pivotally secure the supplemental supports or legs C, which cross each other and project laterally from the ladder between the rear supports and steps when thrown open, as is clearly shown in Fig. 1. In order to allow for the inward and outward throw of the supports, I provide the chain c, which is attached to the rear support and uprights of

the ladder. Said chains have the openings or loops c' formed therein, through which the supports C extend. Thus as the ladder 50 is closed the supports will, by gravity, move inward or close together, so as to be out of the way, and as the ladder is opened the supplemental supports will be thereby extended. Any suitable device may be employed in place 55 of the chains c with equally good effect.

To the platform a, I secure the plate d, to which is pivoted the clamp-plate d', each of which have the opening d' formed therein, through which the rod D passes. The outer 60 ends of plate d and clamp-plate d' are connected by means of the thumb-screw e. The rod extends downwardly through openings e' formed in the ladder-steps, but by means of the clamp-plate is prevented from moving 65 out of its adjusted position. The outer end of the adjustable rod is bent so as to form the hook f, over which the handle of the basket is adapted to hang. By the adjustable rod I am enabled to raise or lower the basket 70 to any desired height.

By constructing the ladder in accordance with the above description the picker is permitted to stand upright upon the platform thereof, without fear of the same tilting or 75 falling over, and at the same time so adjust the holding-rod as to bring the basket to any desired height, thereby obviating the necessity of bending or stooping for the purpose of placing the fruit therein or bruising the 80 same by dropping therein.

I am aware that minor changes may be made in the construction of ladders herein shown and described without necessitating or creating a departure from the nature and 85 scope of my invention.

Having thus described my invention, what I claim as new, and desire to secure protection in by Letters Patent of the United States, is—

1. The step-ladder having the supplemental 90 supports pivotally secured thereto and adapted to be extended by the movement or extension of the propping-legs of the step-ladder, substantially as set forth.

2. The step-ladder having the supplemental supports pivotally secured thereto, and having connection by suitable means with the ladder and its ordinary pivoted or extensible supports, substantially as specified.

3. The step-ladder having the fruit-holding rod held adjustably thereto by the hinge-clamp, the leaves or plates thereof being engaged by an adjusting-screw, and said rod

passing through said plates or leaves, substantially as set forth.

In testimony whereof I affix my signature in presence of two witnesses.

GEORGE TAUSE CAMPBELL.
